UNITED STATES PATENT OFFICE.

S. LEWIS HOLMES, OF HILLSBOROUGH, OHIO.

CAR-COUPING.

SPECIFICATION forming part of Letters Patent No. 267,581, dated November 14, 1882.

Application filed September 7, 1882. (No model.)

To all whom it may concern:

Be it known that I, SAMUEL LEWIS HOLMES, of Hillsborough, in the county of Highland and State of Ohio, have invented a new and 5 Improved Car-Coupling, of which the following is a full, clear, and exact description.

My invention consists of devices to hold up the coupling-pin so that the link will enter, and then trip the pin from either side of the 10 car and let it fall and secure the link; also, a link-lifting device whereby the link can be lifted up to enter and couple from the sides of the car, to avoid the danger of entering between the cars for coupling, the said devices 15 being applicable, with slight changes of form, to the draw-bars of any form in use, as herein-after fully described.

Reference is to be had to the accompanying drawings, forming part of this specification, in 20 which similar letters of reference indicate corresponding parts in both the figures.

Figure 1 is a perspective view of the end of a freight-car having my improved devices applied. Fig. 2 is a longitudinal section of the 25 draw-bar and link and side elevation of the holding-up and tripping apparatus and part of the car.

I arrange a guard-ring, *a*, over the pin-hole *b* of the draw-bar *c*, to hold the lower end of 30 the pin *m*, said ring being formed on the end of an arm, *d*, which is supported a suitable distance back of the pin-hole on the draw-bar by any suitable block, *e*. I prefer to attach it to a block *e* by the cross-bar or T-head *f*, 35 with screws, and to this bar I fix another arm, *g*, which rises up and extends to a point over the ring *a*, where it has an eye, *h*, to receive a point or extension, *j*, of the pin above the head *k*, and together with these arms I provide a 40 tripping-plate, *l*, to slide under the pin *m*,

when it is set up in them, and to this tripper I connect a lever, *n*, to each side, and extending to the sides of the car, respectively, said levers being pivoted at *o* to brackets projecting from the car, and also being arranged in 45 the guards *p* to hold and steady the outer ends. Together with these devices for inserting the pin, I propose to employ a link-lifter consisting of the shaft *q*, with handles *s* and crank *t*, arranged across the end of the car in 50 bearings *u*, so as to be worked from either side of the car to lift the link *v* up level, and hold it for entering the draw-bar of the car to be coupled on by the crank *t*, which swings up forward of the draw-bar.

Thus it is only needful to enter between the cars to set the pin before they are set in motion for coupling, and when there is no danger. The rest may be safely attended to by one at 55 the side of the cars, as will be clearly understood.

It will be seen that the apparatus is applicable to any form of draw-bars with slight modifications of the forms and proportions of the parts.

Having thus described my invention, what I 60 claim as new, and desire to secure by Letters Patent, is—

The combination, with a draw-head having the pin-hole *b*, an arm, *d*, carrying a ring registering with the pin-hole, the arm *g*, having eye *h* over the ring, and the tripping-plate *l*, arranged to slide between the ring and draw-head, of the side levers, *n*, whereby the pin may be caused to drop from either side of the 75 car, as described.

S. LEWIS HOLMES.
